WEAVING OF KNOTTED TUFT FABRIC

Walter A. Rice, Yonkers, and Frank G. Shinn,
Bronxville, N. Y.

Application January 31, 1933, Serial No. 654,469

5 Claims. (Cl. 139—6)

Our invention relates to a method for weaving Persian-knot fabrics.

A purpose is to adapt methods of oriental knot formation to use in modern weaving equipment such, for example, as the Axminster type of loom.

A further purpose is to form a tuft yarn knot by combined movable tubes and movable grippers operating as close to the fell as possible.

A further purpose is to form the knots between the reed and the fell while the reed is maintained continuously in the warp ready to beat up the knots and weft threads.

A further purpose is to avoid failures in synchronism in knot-holding mechanism such as are likely to occur where a knot is transferred any considerable distance along warp threads.

A further purpose is to hold one end of the tuft yarn which in different forms may be the free end or the tube end thereof, but preferably both ends of the tuft yarn, substantially at the fell while the knot is being formed in close proximity to the retained end, producing a knot so close to the fell as to retain its tuft length during the beating operation.

A further purpose is to use a yarn tube, or other device by which the yarn is manipulated which passes through crossed warp threads as the means of advancing the point of crossing of the warp threads to a point close to the fell before the yarn is drawn off, thus facilitating the weaving of a low pile.

A further purpose is to space the warp threads uniformly at the reed, one thread to each space between reed dents and to pair the warp threads at the fell.

A further purpose is positively to hold the free end of the knot-forming yarn at the fell and to retain the other end in guides also at the fell during the final knot-forming operation and during beating up.

A further purpose is to shift the free end of a tuft of pile yarn from a position above the warp at a distance from the fell down through between crossed warp threads at the rear of the crossing point, forwardly toward the fell and upwardly in front of the crossing point and there hold it while drawing out the yarn to form the knot, subsequently using a guide by which the yarn has been inserted to advance the position of the crossing to a point close to the fell and, while it is so advanced, to bring the attached end of the yarn up substantially to the fell and then introduce a weft or binder prior to cutting.

A further purpose is to utilize tubes and grippers extending down under the crossed warp

threads in front of and back of the crossing point or vice versa, to pass a pile yarn under the crossing, subsequently withdrawing the tubes and grippers and to form the knot thus provided substantially at the fell, holding both ends of the knot so formed at the fell until after the knot has been beaten up and bound in by weft.

In the weaving of tufted fabrics a further purpose is to save loom time of transferring knots from the position at which they are made to the fell by forming the knots substantially at the fell so that no transfer other than beating is required.

A further purpose is alternatively to form right or left hand Persian knots, determining the character of the knots by the selection and direction of transfer of one or other of a pair of warp threads crossed over its mating thread of the pair.

A further purpose is to use combined tube and gripper mechanism on opposite sides of a crossing point within a pair of warp threads as a means of passing a tuft yarn from one end of the crossing to the other, preliminarily using the yarn tube or gripper initially carrying the tuft yarn to effect crossing in the warp threads.

A further purpose is to move tuft yarn conveying tubes to position between pairs of laterally movable spring clamp fingers, and to then withdraw the tubes from between the fingers, leaving one end of the tuft yarn clamped therebetween.

Further purposes will appear in the specification and in the claims.

We have preferred to illustrate one main type with slight variations, selecting a type which is practical and effective but which has been selected chiefly because of its value in illustration of the principles involved.

Figures 1, 3, 5 and 10 are diagrammatic plan views of loom parts used in carrying out our invention, the parts being positioned to represent parts of a cycle of weaving operation.

Figures 2, 4, 6, 7, 8, 9, 11 and 12 are diagrammatic vertical sections parallel to the lengths of the warp threads, showing successive positions in a cycle of loom operation. Of these Figures 2, 4, 6 and 11 are taken upon lines 2—2, 4—4, 6—6, and 11—11 of Figures 1, 3, 5 and 10.

Figures 13 to 18 are diagrammatic fragmentary perspective sections illustrating steps in our process or method.

Figures 19, 21, 23 and 28 are fragmentary diagrammatic plan views showing successive steps in our method or process, crossing the warp threads in a slightly different way from that in the preceding figures.

Figures 20, 22, 24, 25, 26, 27, 29 and 30 are

fragmentary diagrammatic vertical sections lengthwise of the warp threads further illustrating the several steps of our invention. Of these Figures 20, 22, 24 and 29 are sections upon lines 5 20—20, 22—22, 24—24 and 29—29 of Figures 19, 21, 23 and 28 respectively.

Figures 31 and 33 are fragmentary vertical sections and Figures 32 and 34 are fragmentary side elevations of Figure 31 and Figure 33 respectively, illustrating gripper operation.

Figures 35 and 36 are perspectives showing several of the positions of the previous figures, but reversing the tuft carrying members in the other figures.

Figures 37, 39, 41, 43, 45 and 47 are fragmentary sections across the warp threads showing a plurality of warp thread pairs and the associated operating members and corresponding generally to sections taken upon single warp thread pairs 20 at 37—37, 39—39, 41—41, 43—43, 45—45, 47—47, of Figures 38, 40, 42, 44, 46, 48 and 50 respectively.

Figures 38, 42, 44, 46, 48, and 50 are perspective views showing the various positions of the warp threads, tuft yarn, crossing comb, tuft yarn tube 25 and gripper in the formation of a Persian knot.

Figures 49 and 50 show in section upon line 49—49 and in perspective a plurality of finished loops in loose formation and a single loop upon a single pair of warp threads respectively.

Figures 51 and 52 show in section similar to that of Figure 49 different arrangements of knots with respect to the warp threads from the arrangement shown in Figure 49.

In the drawings similar numerals indicate like parts.

This case is in part a continuation of our application for patent for Method and apparatus of weaving knotted fabrics, Serial No. 533,846, filed April 29, 1931, and is intended to cover the subject matter which in that case is specific to the use of two devices for manipulating a tuft yarn, one a yarn tube and the other a gripper, which meet below the warp threads of a pair and transfer the yarn from one to the other by which the 40 yarn is passed as a loop under crossed warp threads.

In the illustration the uncrossing of the warp threads transforms the loops thus made into knots. It is the intention to cover in the application to which reference is made above the broad subject matter applicable to the form of our invention shown in this case and to any other form or other forms shown in that application.

Our invention is directed to the machine production of knotted fabrics using the Persian knot, whether in rugs, carpets or tapestry. The product is intended to correspond with the well-known hand-formed Persian rug and tapestry products, and our process, and mechanism are, 60 therefore, confined to the movements of elements—which may be moved by hand—to facilitate tying of these knots, but which, for commercial operation, must be operated by machinery.

The fragmentary illustrations shown are capable of being hand-operated, but the advantage to be secured lies in the fact that these fragmentary showings are suitable for assembly as parts of a large machine operation which can be made up of a large number of like units in coincident operation.

In the various illustrations shown we have passed the free end of a tuft yarn between crossed warp threads in the rear of the crossing point of crossed warp threads to the front of the same so 70 as to emerge close to the fell, or have passed the

tuft yarn in the opposite direction, drawing off the 5 yarn to supply a knot, bringing the attached end of the yarn around also or retaining it close to the fell. The two ends of the yarn are brought substantially together at the fell and are held there taut while the weft or wefts are inserted and are beaten up, securing uniformity of the ends and avoiding slack yarn at the back of the fabric. The attached end is finally severed.

For convenience in dealing with the various 10 forms, we will treat the devices by which the tuft yarns are manipulated as of two classes only, namely, "tubes" when the yarn passes through them, and "grippers", where the yarn is firmly held by the device and the device is moved to 15 manipulate the yarn by the movement thereof, whether these belong to the gripper class as ordinarily viewed by textile workers or to the needle class.

Where the tubes are intended to perform the 20 additional function of laterally engaging alternate warp threads to cross them over intervening warp threads, the shed formation to facilitate this purpose is preferably the first step.

In the illustration the warp threads initially 25 lie in levelled position for the beginning of a cycle of operation. A tuft yarn tube preferably of the Axminster type is positioned to enter the warp threads and pairs of clamping fingers comprising grippers are positioned to receive the tuft 30 yarns from the tubes, one gripper for each tube.

In carrying out our invention we employ a plurality of warp threads arranged to be operated upon in pairs, and being here designated 55, 56, 55', 56', 55', 56', etc. These threads pass from a 35 fell 57 (which preferably is fixed in position by the use of take-up mechanism, and may therefore correspond with a breast 58) back through the usual loom reed to heddles 59 and 60. Each thread passes through the eye of one of the 40 heddles so that shedding of the warp threads can be effected by them. The threads pass over the usual tensioning devices to a source of warp thread supply or beam (not shown) at the rear of the loom.

The usual shuttle 61 is carried by the shuttle frame 62 which is adapted to be shot back and forth across the lay by a conventional picker motion (not shown) in a manner common and well known in the weaving art, in order to place 50 one or more weft or filling threads. While we have herein illustrated a shuttle as the means for inserting the weft or filling, we desire it to be understood that we contemplate (alternatively) using the regulation Axminster needle for the 55 same purpose, if desired, in which case a double weft shot will be placed after the formation of each row of loops or knots and before any change is made in the shed.

The yarn intended for the formation of the 60 yarn tufts is carried upon spools 63 which are rotatable within frames carried by an endless chain 64, as is common in Axminster weaving. The tuft yarn is fed through tubes 65 which are integral with the frames. The frame units, comprising the frame, tubes and spool, are detachable one at a time from the endless chain for introduction to the knot forming mechanism. After an individual frame has been acted upon by the knot forming mechanism, it is returned to 70 the endless carrier chain, and the chain is moved to bring the next adjoining frame unit into registry with the transferring mechanism. From the time a frame unit is taken from the chain until it is returned thereto and the chain is moved 75.

to bring the next frame into register for a succeeding operation, constitutes a cycle which completes a row or shot of the weave.

The chain is carried by the usual sprocket 66 and the frame, when free from the chain, is handled by arms 67, one at each side, rock shaft 68 (pivoted in the frame at 69) and rod 70.

The arms 67 not only convey the frames from the chain and back to it but, with the assistance of allied mechanism, carry them through a cycle of knot forming operation.

The frame and tube mechanism just described is generically old in the Axminster loom art, and the general control of the movement is intended to be the same as in that art, i. e. by suitable cams, etc., but the specific movements given and the timing of these movements will, of course, be suited to our processes and methods.

The yarn supplied from the spool is threaded through the tubes 65, and projects from the bottoms of the tubes to present free ends 71, one to each pair of warp threads within the loom.

Close to the fell we support a guiding comb of which two types are shown at 72 and 72' respectively, that shown at 72 being seen in Figures 1 to 18 and 72' being shown in the remaining figures.

The teeth 76 are guiding or spacing teeth, to draw together into pairs at the fell warp threads which are uniformly distributed at the reed, one warp thread to each space between reed dents, a construction which is believed to be new to us, whereas the comb 72' maintains at the fell a pairing of warp threads which already exists in that two warp threads pass through each space.

35 The comb 72 or 72' is mounted upon arms 73 pivoted at a point not shown and is controlled in its movements by a rod 74 pivoted to the arms at 75; with the purpose and intent that the comb may be lifted into the position shown in Figure 2, or lowered out of the way as desired. There is also an advantage in adapting the comb to shift perpendicularly of the paper in Figure 2.

The comb 72 is provided with teeth 76, one for each pair of otherwise uniformly spaced warp threads. Between the teeth are slots 77 and the upper faces 78 of the teeth are tapered toward the slots so that when the comb is raised from beneath the pairs of warp threads it will bring two warp threads together into each slot.

50 Normally one of each of these pairs of warp threads will coincide approximately with the slot positions and the other threads of the pairs will be engaged by intermediate parts of the sloping tooth surfaces and will be guided into the respective slots. This is for a purpose, the need of which is afterward more clearly shown, of providing wider spacing between the two warp threads of each pair than the normal spacing between these warp threads, facilitating the passage between the warp threads of each pair of a device for manipulating a tuft yarn.

Since the spacing to be provided is between the two warp threads of the same pair it will be clear that the warp threads fitting into any one of the 65 slots are not the warp threads of the same pair, but warp threads in different positions in adjoining pairs, that is, the adjoining warp threads of different but adjoining pairs.

Whether a comb be used or not, and whether 70 the comb of the first eighteen figures be used or not, it is the intention in the process or method claimed herein to cross the individual warp threads of each pair upon which the same knots are to be formed, one warp thread of the pair 75 over its mating warp thread of the pair, in order

that one of the two crossings so formed can be used to assist in the formation of the Persian knot on this pair.

As the initial step to the crossing when formed by the methods shown, we form a shed of the warp threads, which need not be a complete shed, one thread from each pair being placed in the upper shed level, as seen at 55² in Figure 2, and the others, one from each pair of warp threads being placed in the lower shed level, as seen at 56² in the same figure.

The yarn manipulators—here the tubes 65—are then dipped beneath the upper shed level—unless they have previously been placed in this position—so that when laterally moved they will 15 engage with the upper shed level warp threads 55² and carry these warp threads with them.

The yarn manipulators, here tubes 65 are then shifted laterally to what, for purposes of description, may be considered an excessive distance, 20 i. e. further than the distance at which they are intended ultimately to rest. This brings these yarn tubes laterally beyond the positions of the warp threads 56, 56', 56² (Fig. 3) so that when these warp threads 56, are lifted, or when the 25 warp threads 55, 55', 55² to engage the warp threads 56, 56', 56² when the yarn tubes 65 are 30 laterally moved in the opposite direction to their first movement, that is, in retracting direction.

In Figures 3 and 4 the lateral positions of the tubes 65 are shown in Figure 3 and the height of the tube with respect to the heights of the warp threads 55² and 56² are shown. In this position of the parts the threads corresponding to 56² have not yet been shifted high enough to be engaged by the tube, nor has the tube been lowered far enough to engage the threads. The parts are 40 therefore not yet in position for the tubes to be eased back toward their positions in Figure 1.

When the threads 56, 56', 56² have been lifted or the tubes have been dipped further so as to provide for lateral engagement the tubes 65 are 45 moved back to lateral position corresponding with their initial position in Figure 1. This results in easing the lateral displacement of the threads 55, 55', 55² and laterally displacing threads 56, 56', 56² in a direction reverse to that of the displacement of the threads 55, 55', 55², balancing the displacements of the threads, reducing the tension upon threads 55, 55', 55² and releasing the tension upon these threads as compared with threads 56, 56' and 56². 55

The result of the lateral displacement of threads 55, 55', 55² in one direction and 56, 56', 56² in the opposite direction, 55, 56, 55' and 56' and 55² and 56², respectively, lying on opposite sides of their several tubes is to form two sets 60 of crossings of the threads one, 79 near the fell between the tubes and the fell and the other set 80 between the tubes and the lay. The crossings correspond to those shown in Figures 5 and 6 but the tubes are not in the same positions 65 as to distance from the fell as in Figures 3 and 4, having swung toward the fell at the same time that they have dipped further between the warp threads.

The crossings 79 are used by us in the formation of our knots, while the crossings 80 are, for our purpose, accidental, idle and resultant crossings which are not used except as their presence with the tension in the warp threads makes ultimate withdrawal of the tuft yarn tube 65 from 75

its position within the warp threads result in uncrossing the warp threads, changing the tuft yarns laid as U loops, each in a single plane parallel to the length of the warp threads, into Persian knots.

The devices for manipulating the tuft yarn, whether tubes as in Figures 1 to 34, or grippers as in Figures 35 and 36, are intended to cooperate with other tuft yarn manipulators, either grippers as in Figures 1 to 34, or tubes as in Figures 35 and 36, located upon opposite "sides" of the crossings 79 considered in a direction longitudinal to the tuft yarns. This means that in Figures 1-34 one of each pair of grippers during operation passes between the crossed warp threads of the pair back of the crossing 79, while the other device, here a tuft yarn tube during operation passes between the threads of the same pair but in a position between the crossing point and the fell. The expression "opposite sides of the crossing" is used here notwithstanding that it may be a misnomer for "opposite ends of the crossing", because of the very general use of "opposite sides" to express such a situation and without the intention of indicating relative lateral positions.

In Figures 1 to 34 the tubes 65 cooperate with grippers 81, which, in Figures 1 and 2, are shown as passing through between the warp threads of the individual pairs. Preferably these grippers will not be passed between the warp threads of individual pairs until after the comb 12 has been raised to divide the warp threads, because of the desirability of having extra warp thread spacing for the grippers, but the grippers may pass between the warp threads, before or after crossing of the warp thread, to be in position to engage the projecting tuft yarn ends in proper sequence of operation.

The use of grippers in weaving operations is old, and the several movements to be given to them are, therefore, well within the range of the designer. For this reason it has not been considered necessary to illustrate operating mechanism for bodily movement of the grippers, nor for opening and closing them in proper order so as to have them engage the tuft yarn ends 71.

It is desirable to have the knots as "laid" located as close to the fell as possible in order that there may be as little disarrangement of the knots as permissible during the operation of beating up the knots against the fell, whether the knots be beaten up separately or in conjunction with the beating up of weft yarns, separating the successive rows of knots.

We provide progressive transfer of the knot positions toward the fell during the operation of laying the knots by progressive shifting of the crossing points of the warp threads of the pairs toward the fell during the knotting operation. This is effected by bodily movement of that tuft yarn manipulator farther from the fell, whether it be tube or gripper, toward the fell during the successive operations performed by it. The fact of progressive bodily movement will be apparent from the successive positions of the tubes 65 toward the fell, seen in the several positions of Figures 2, 4, 6, 8, 9, 11 and 12.

After the crossing of the warp threads has been effected, as described, the manipulating devices farther from the fell, here tubes 65, swing about the axis 69 and at the same time move bodily toward the fell, carrying the tuft yarns with them from the positions in Figures 6 and 15 to the positions shown in Figures 8 and 16, where

the tuft yarn grippers 81, are open to receive the tuft yarn and do engage and hold the projecting tuft yarn ends 71, after which the ends 71 are withdrawn by upward movement of the grippers 81, preferably in a general direction of their lengths with bodily movement toward the fell, bringing them initially to some such position as seen in Figure 9. They are held preferably at or near the position shown in Figure 9. The exact relation between the time of their movement to this position and the time of movement of the tuft yarn tubes 65 is not vital to the theory of the operation but does affect seriously the question of the complete time taken for the operation.

The necessity for rapid operation makes it very desirable that the movements of these several parts be concurrent instead of successive, and, therefore, that the tube carrier 65 be moved upwardly as the tuft yarn gripper 81 is moved upwardly; with the qualification, however, that the gripper 81 should preferably pull out of the tube 65 a sufficient length of tuft yarn to provide for a full movement of gripper 81 in making the knot before the tuft yarn tube 65 leaves the warp threads, in order that the part of the tuft yarn forming the body of the knot need not be subsequently pulled through. As the tube is lifted it will expose the tuft yarn end with little or no physical movement of this end during the tube movement.

The tuft yarn tube 65 continues its upward movement preferably at the same time advancing toward the fell and ultimately leaves the warp threads, shifting from the position of Figure 9 to that of Figure 11 at which, or just before which, the knot can be beaten up by the reed 62.

It will be noted that both ends of the tuft yarn are held in Figure 11 during the beating up, the tuft yarn end being held by the grippers 81 and 40 the attached portion of the tuft yarn being held by its connection through the tuft yarn tube with the spool where any desired braking can be had.

In the position of Figure 11 the tuft yarn gripper 81 can be located high enough to permit cutting of what has been called the free end 71 by the knife 82 or the exact positioning of the free ends of the tuft yarn may be relied upon to give them proper length without cutting. In either event the attached end of the tuft yarn is cut by 50 the knife in the position of Figure 12.

The perspectives of Figures 13 to 18 show various steps. The divided but uncrossed warp threads are shown in Figure 13 with the two threads in the same slot from different pairs. In Figure 14 the upper warp threads have been crossed over the lower warp threads far enough for the tubes to have passed laterally beyond the lower warp threads with which the respective warp threads are to be paired. In Figure 15 the tubes have come back to position for symmetrical crossing of the warp threads.

In Figure 17 the warp threads have been crossed in the opposite direction, that is, the warp threads which form the lower position in the 65 shedding of Figure 14 are in the upper position in Figure 17, with the result that the crossing must be effected by movement of the tubes in the opposite lateral direction from the initial movement of the tubes in Figure 14. For this 70 reason instead of producing right-handed knots shown in Figures 47, 49 and 52, as in the operation including the movement of Figure 14, left-handed knots, such as are shown in Figure 51, are produced when the operation is reversed as 75

in Figure 17. The formation of right and left knots may be alternated, weaving first right knots and then left knots in alternation.

Whichever the type of knot initially planned and produced, the "knotting" does not become effective in these figures until release of the diverted warp threads by removal of the tube from its position between them.

In Figures 19 to 30 and 37 to 50 the comb 72' at the fell differs from the comb in the earlier figures in that the comb slots 77' correspond in number and spacing with the number and normal spacing of the warp threads. Since two warp threads pass through each space between adjoining reed dents, the warp threads here are already pairs. In this case also the pairing is different from the pairing ultimately effected by the knots common to both warp threads of the final pairs. They are intended to hold two warp threads each and to maintain the spacing of the warp threads during the several operations up to the time when the knots are ready to be beaten up. The chief advantage of the use of this comb lies in preventing the warp threads within the individual pairs from being displaced toward each other during the crossing of the warp threads and while they are crossed, thus maintaining better spacing than would otherwise be provided for the grippers 81 in their passage between the warp threads. Even if the grippers 81 be passed through the spaces between the pairs of warp threads before the crossing takes place the comb maintains warp thread spacing and thus renders the operation more trustworthy and reliable than in the absence of the comb; and where it is desired to insert the grippers after the crossing, crowding at the fell of the individual warp threads of the pairs to be knotted together is prevented.

In Figures 19 to 30 the crossing of the warp threads is effected by movement of the lower warp threads of the pair in the shedding shown. With the same shedding this will, of course, mean that the lower warp threads must be moved in a direction opposite to the direction of the movement of the upper warp threads in order to effect the crossing and that the same kind of knots will be produced, namely, right-hand knots if right-hand knots would be produced by crossing the upper threads and vice versa. To produce opposite knots, as compared with those produced by shifting the upper warp threads of the pairs the shedding must be reversed to place in the lower shed level those warp threads of the pairs which otherwise would appear in the upper shed level.

The crossing operations are illustrated in Figures 19 to 24 and 39 to 42 in which after the shedding the threads of the lower shed level are engaged by pins 83 upon bars 84 which may be shifted vertically to bring the pins within the warp threads, or about which the warp threads may be shifted downwardly to bring them in line with the pins.

In either event the warp threads are shifted laterally from the positions seen in Figures 19 and 20 to the positions seen in Figures 21 and 22. In the latter positions the warp threads have been shifted toward the lower part of the sheet to an excessive extent. They then lie beyond the complementary warp threads of the several pairs so that with further upward shifting of the pins or with downward shifting of the upper warp threads the complementary warp threads of the pair will be in position laterally to be engaged by the pins.

Reverse lateral shifting of the pins will now divert the complementary warp threads of the pairs to an extent seen in Figure 23 and at the same time will slightly release from their lateral tension those warp threads which were initially shifted, giving a crossing which is symmetrical in each pair and which is best seen in Figure 23.

As seen in Figure 24 the warp threads may be level before or after the second (reverse) lateral shift of the pins takes place, bringing the warp threads to a common shed level for the further operation upon them.

By illustrating two means of crossing the warp threads, both of which act upon shedded warp threads pushing them laterally at points located between the fell and the reed, it is not intended to give the impression that these are the only ways to secure the shifting of the warp threads to cooperate with other features of our invention, such, for example, as with the use of the tuft yarn tubes or grippers to force the crossing point up toward the fell. This cooperates well with the crossings shown but will cooperate also with a crossing in the warp threads however formed.

Instead of effecting the shifting of the warp threads by the tuft yarn tubes, as in Figures 1 to 18, and by this means placing the tuft yarn tubes between the warp threads as part of the warp thread shifting operation, the tuft yarn carriers in later numbered figures are passed between the warp threads after the warp threads have been crossed, that is, between the positions of Figures 22 and 24.

From the positions of Figures 23 and 24 at which the tuft yarn carriers lie within the warp threads the operation shown in Figures 19 to 50 is substantially the same as that intended to be shown in Figures 1 to 18, but with the difference that the pins 83 and bars 84, though no longer needed after the crossing of the warp threads are to be reckoned with to the extent that they must be kept out of the way of the operating parts, which means both that they must not interfere with positioning the tubes 65 nor with the subsequent movement of these tubes, and that they must be kept out of the way of the lay in the subsequent placing of the weft thread and beating up of the tuft yarn knots and of the weft thread, whether they be beaten up separately or together.

In Figures 19 and 20, 37 and 38 the parts are in position for the beginning of the cycle except that the comb 72' is in position within the warp threads, the grippers have been passed between the warp threads of the individual pairs and the pins 83 in Figs. 19 and 20 have been placed within the lower warp thread range for shedding of the warp threads. In Figures 38, 40, 42, 44, 46, 48 and 50 the disclosure of a single pair only results in showing but one warp thread to each comb whereas with this form of comb it is intended to gather together within each comb slot two warp threads, one each from adjoining warp thread pairs as seen in Figures 13 to 15 and 17.

In Figures 21 and 22, 39 and 40, the first (relatively excessive) lateral shift of the warp threads by the pins has taken place and in Figures 23 and 24 the pins have engaged with the other (complementary) warp threads of the pairs, shifting them laterally and permitting the first warp threads engaged to move back to a position of symmetry in crossing, the warp threads having been brought to a common level and the tubes having been dipped beneath the common shed level and between the crossed warp threads upon

the side of the crossings of these warp threads away from the fell.

In Figure 25 the tubes have progressively moved bodily in clockwise direction in the figures from the position of Figure 24 to the position of Figure 25, carrying the tuft yarn and forcing crossing toward the fell, until they have reached a point where the previously opened gripper fingers 85 and 86 engage opposite sides of the tubes at the lower ends of the tubes.

Between the positions of Figures 25 and 26 the tubes move up or the grippers move down so that the grippers slip over the ends of the tubes, engaging with the tuft yarn ends 71 carried by the tubes.

These last two positions are shown in Figures 41, 42, 43, and 44 respectively.

Though the movements of the tubes and grippers are preferably gradual and progressive and as far as possible take place concurrently, in order to save weaving time, it is not essential from the theory of the operation that the movements shall be concurrent. Whether this be true or not the next step is in the withdrawal of sufficient lengths 25 of tuft yarn from the respective tubes for the knot formation. This preferably takes place for the most part during the movement of the grippers from the positions shown in Figures 26 and 44 to the positions shown in Figures 27 and 46 30 and before the tuft yarn carrying tubes are withdrawn from their positions between the crossed warp threads of the respective pairs on the sides of the crossing away from the fell. Some of the tuft yarn within the tube will be exposed, of course, (to form one tuft end of the knot) as the tube is further lifted. The purpose of this is to place the tuft yarn lengths thus drawn out, in proper position around under from one side to the other, (here back to front or front to back), 35 of the crossing in the position close to the fell.

Whether the entire lengths of tuft yarn be withdrawn before the tubes emerge from the warp thread shed or not the pins 83 are preferably withdrawn from their positions between the warp threads of the respective pairs before those carriers located back of the crossings are lifted out of the warp threads, resulting in immediate straightening (uncrossing) of the warp threads of the respective pairs as soon as the tuft 45 yarn tubes are withdrawn from between them. When this takes place the tuft yarns which have previously comprised loops across the crossings from front to back, or back to front, are converted into Persian knots, as seen in Figures 47-52 at points very close to the fell, with the definite advantage that they require but slight movement along the warp threads during the operation of beating up.

By comparing the positions of the tubes in Figures 27-30 and in Figures 46 and 48, it will be seen that the tubes preferably progressively advance bodily toward the fell during this latter part of the operation also, additionally advancing the tuft yarn knots toward the fell and reducing the distance through which these tuft yarn loops need to be driven when they are beaten up. For convenience in placing the grippers between the threads of adjoining pairs of warp threads with a minimum of spacing the warp thread fingers 65 70 85, 86 for different tuft yarn tubes may be placed in different levels initially as seen in Figures 31 to 33.

Though a breast plate is shown mounted to swing about an axis 88 and held by spring 89 against a stop 90 it will be evident that this is not

essential and that if used its detail—as in the case of the detail of the other structure shown—need not be followed.

Our processes and methods facilitate the formation of an extremely low pile without shearing, thereby avoiding waste of the more costly yarn comprising the pile product. They also permit of pile formation of varying pile lengths while still retaining all of the advantages of forming the knots close to the fell. This shortness of knot 10 movement combined with the holding of both ends of the tuft yarn during the loop or knot formation, maintain the initial tight contacts of the tuft yarn of the knots with the warp threads, and at the same time secure uniform height for 15 both tufts. Variation in the character of the tuft yarn tubes or grippers, in the direction of their movement and in the cooperation with other mechanism may take place without losing these advantages.

The final movements of the frame and tubes from the position of Figures 9 and 27 are preferably upward and forward but obviously the movements of rotation and the vertical movements of the tubes can be combined to form composite paths of movement, preferably to a position shown in Figure 11 or 12, in which, or in some similar position, the tubes are held stationary in their travel while a second shed is formed in the warp threads, and one or more 20 shots of weft yarn are put in and beaten up. It is not intended here to indicate that the beating up of the knots must wait for the placing of the weft but ordinarily this will be the case.

The accurate predetermination of the lengths 30 of the "free ends" of the yarn permits use of this free end without cutting as a measure of the height of the pile while weaving a very low pile fabric.

It will be evident that in the reversal of parts 40 illustrated in Figures 35 and 36 where the tuft yarn guide is at the fell and the grippers enter through the rear of the crossing, the tuft yarn guide 68' can be inserted between the warp threads of the pair either before or after the 45 crossing of the warp threads. The warp threads need not be crossed in one particular way. The gripper 81' is used to effect the movement of the crossing toward the fell and any relation of movement between the tuft yarn guide and gripper can be used which may be desired to insure pulling the proper amount of tuft yarn from the guide which may be desired—and no more—by concurrent or separate movements of these 50 parts.

It will be evident that whatever the number of 55 weft threads 91 laid after each course of tuft yarn knots, the knots and the weft yarn can be beaten up separately if desired, or concurrently at the wish of the designer.

It is not the intention of this application to 60 stress special relations of weft threads to the knots or warp threads, but to indicate instead that our invention is suitable for use with a considerable variety of weft thread introduction, placing the weft threads after the knots have been formed with any suitable shedding of the warp threads and in any quantity of weft threads in one placing which may be desired—singly, as with a shuttle, double, as with a shuttle or with a needle or in any multiples of either that may be dictated by the character of ultimate weft 65 70 75 which is desired.

It will be evident that all of our work is done 75 without interference from the reeds, whose dents

remain in the warp threads at all times. Our methods and apparatus do not require deviation of the warp threads from their normal horizontal position except as the warp threads must be formed in sheds and must be crossed.

It will be evident that the method and mechanism applying the tapered comb teeth of Figures 1 to 18 and the single warp threads per space between the dents facilitates a finer weave than in the method and structure of the other figures.

This condition permits application of our invention to normal looms with normal loom operating mechanisms contemplating a minimum of change. The changes required are rather changes of addition than of alteration.

It will be evident that the same methods which apply to the formation of right-hand Persian knots 92, as seen in Figures 47 to 50, are applicable also to the formation of left-hand Persian knots, such as are seen in Figure 51, and that the rows of knots can be alternated one row right-hand and the other row left-hand by the simple expedient of reversing the shedding, and either reversing the direction of crossing or shedding by movement in the upper shed level where the lower shed level had previously been used or vice versa.

In view of our invention and disclosure variations and modifications to meet individual whims or particular need will doubtless become evident to others skilled in the art, to obtain part or all of the benefits of our invention without copying the structure shown, and we, therefore, claim all such in so far as they fall within the reasonable spirit and scope of our invention.

Having thus described our invention, what we claim as new and desire to secure by Letters Patent is:

1. The method of weaving a rug in a loom having warp threads in pairs, means for shedding the warp threads, and yarn tubes and grippers, which consists in partly shedding the warp threads with the two threads of each warp thread pair in different shed levels, in crossing one warp thread over the other within each of the pairs by lateral movement of the yarn tube, in dipping the yarn tubes used to effect the crossings further between the warp threads, in passing the grippers down between the warp threads on the fell side of the crossings, in transferring the ends of the tuft yarn from the yarn tubes to the grippers beneath the warp threads and in removing both the yarn tubes and grippers from beneath the warp threads and concurrently uncrossing the warp threads.

2. The method of weaving a rug in a loom having warp threads in pairs, means for shedding the warp threads and tuft yarn tubes and grippers, which consists in partly shedding the warp threads with the two threads of each warp thread pair in different shed levels, in crossing the warp threads within each of the pairs by lateral movement of the tubes, in dipping the yarn tubes used to effect the crossings further between the

warp threads on one side each of the corresponding warp thread pair crossings, in passing the grippers down between the warp threads on the opposite side of the crossings, in transferring the ends of the tuft yarn from the yarn tubes to the grippers beneath the warp threads, in forcing the crossing points of the pairs close to the fell while the tuft yarn tubes by which the crossings have been effected are still in the warp threads, in uncrossing the warp thread pairs by removal of the yarn tubes while maintaining the hold upon one end each of the tuft yarns and in beating up the knots so formed while maintaining the hold upon the tuft yarns.

3. In the operation of tying Persian knots about warp threads in a loom using warp threads, weft threads, wires and two sets of movable tuft yarn manipulators, one set comprising tubes and the other set adapted to withdraw tuft yarn from the tubes, the novelty which consists in shedding the warp threads with threads of individual pairs in different shed levels, in using one set of manipulators to shift one thread of each pair laterally beyond the other thread of each pair to cross the warp threads, in withdrawing the tuft yarns from the tubes by the manipulators at points beneath the warp threads and pulling them up between the warp threads on opposite sides of the crossings all while maintaining the wires in the warp threads, in inserting weft and in beating up the weft and the tuft yarn inserted.

4. In a loom for weaving knotted fabric, warp crossing mechanism and a comb having a tooth for each pair of warp threads, each tooth being high at a point located between the warp threads of its pair, having a slot immediately adjoining this high point on one side and a slope on the other leading to the slot adjoining the high point of the next tooth whereby the warp threads of an individual pair are separated by the sloping part of the tooth and the adjoining threads of different but adjoining pairs of warp threads are collected together in the slots.

5. In the operation of tying Persian knots about warp threads in a loom using warp threads, weft threads, wires and two sets of movable tuft yarn manipulators, one set comprising tubes and the other set adapted to withdraw tuft yarn from the tubes, the novelty which consists in shedding the warp threads with threads of individual pairs in different shed levels, in using one set of manipulators to shift one thread of each pair laterally beyond the other thread of each pair to cross the warp threads, in withdrawing the tuft yarns from the tubes by the manipulators at points beneath the warp threads and pulling them up between the warp threads on opposite sides of the crossings at the same side of the warp, all while maintaining the wires in the warp threads, in inserting weft and in beating up the weft and the tuft yarn inserted.
